UNITED STATES PATENT OFFICE.

JOHN S. BRENNAN, OF MILWAUKEE, WISCONSIN.

VALVE FOR OIL-STOVE RESERVOIRS.

1,376,858.

Specification of Letters Patent. Patented May 3, 1921.

Application filed October 6, 1919. Serial No. 328,796.

To all whom it may concern:

Be it known that I, JOHN S. BRENNAN, a citizen of the United States, and resident of Milwaukee, in the county of Milwaukee and State of Wisconsin, have invented certain new and useful Improvements in Valves for Oil-Stove Reservoirs; and I do hereby declare that the following is a full, clear, and exact description thereof.

- 10 My invention relates to new and useful improvements in valves, more particularly of that type adapted for controlling the flow of fuel liquid from the supply receptacle of oil stoves, such receptacles being invertible 15 over an auxiliary constant level receptacle wherein the level is determined by the bottom plane of the discharge neck of the main receptacle, which projects thereinto, the valve being opened by engagement of its 20 stem with the bottom of the auxiliary receptacle and closing when the main receptacle is lifted from the auxiliary receptacle, thus providing for inversion of the main receptacle without wastage of liquid therefrom. 25 It is in general the object of my invention to simplify and otherwise improve the structure and to increase the efficiency of valves of this character.

It is a more detailed object of my invention to inclose the spring usually employed in valves of this character, and it is more particularly my object to utilize the operating stem of the valve member for housing the spring.

30 With the above and other objects and advantages in view, which will be apparent as the description proceeds, my invention resides in the novel features of construction, combination and arrangement of parts which 35 will be hereinafter more particularly described and defined by the appended claims.

In the accompanying drawings:

Figure 1 is a vertical sectional view through a valve constructed in accordance 40 with my invention, and the usual oil supply reservoir stove associated therewith, the plane of this section with respect to the valve member being indicated by the line 1—1 of Fig. 2.

45 Fig. 2 is a bottom plan view of the valve structure.

Referring now more particularly to the accompanying drawings, 5 designates the usual dispensing or main supply receptacle, 50 which is inverted over the pan-shaped auxiliary receptacle 6, the neck 7 of the main

receptacle depending into the receptacle 6 whereby the bottom plane of the neck 7 determines the liquid level supply in the receptacle 6, which has the usual pipe 8 extending 60 therefrom for supplying oil to the burners of the stove.

My improved valve structure includes a cap member which forms a portion of the valve casing, said cap member comprising a 65 cylindrical wall 9 having threads for engagement on the correspondingly threaded receptacle neck 7, the end of the cap being centrally apertured to provide an outlet port, the cap material surrounding said aperture 70 being inclined inwardly therefrom to form a frusto-conical valve seat 10 which is thus offset inwardly of the plane of the cap end. A substantially dome-shaped inner valve 75 casing section 11 is secured to an inner face of the cap end preferably by tabs 12 passed through the cap end and clenched on its outer surface, this valve casing member being provided with an inlet port 13 in its top, and also with a port 14 at one side. The 80 valve proper is preferably formed from a single piece of metal drawn to provide a cylindrical hollow stem 15 closed at one end and which has its other end flared to provide 85 a frusto-conical valve head portion 16 engageable against the valve seat 10, the stem extending loosely through the outlet port of the casing. An expansile coil spring 17 is disposed in the stem and casing, one end of the spring bearing against the closed end of 90 the stem while the other end of the spring bears against the top of the casing section 11 which is shaped to form a proper seat for the spring 10.

I have thus provided an exceedingly 95 simple, efficient and durable valve structure which may be most economically manufactured and assembled, all of the casing parts comprising simple stamped or drawn members. In assembling the device, the sleeve 100 15 is passed through the outlet opening of the cap, the spring 17 is dropped into the sleeve and the inner dome-shaped casing section 11 is then applied, its tabs being projected through the end of the cap member 105 and clenched whereby the entire device is held in assembled relation, the valve being normally urged outwardly to closing position by the spring, and being released by abutment of the end of the stem 15 with the 110 auxiliary receptacle 6 when the main receptacle is inverted thereover.

While I have shown and described a preferred embodiment of my invention, it will be appreciated that various changes and modifications of structure may be employed to meet differing conditions of use and manufacture, without departing in any manner from the scope of the appended claims.

What is claimed is:

1. A valve structure of the class described comprising a cylindrical casing member adapted to form a receptacle closure member and provided at one end with an annular valve seat, a cup shaped casing member having its open end secured to the first 10 casing member and surrounding said seat, a tubular valve stem extended through the valve seat and having its outer end closed, a valve head enlargement on the inner end of the stem engageable against said seat, and 15 an expansile coil spring disposed in the stem, the coils of the spring being of substantially the same diameter as the inside of said tubular stem, and said spring acting between the outer end of said tubular stem and 20 the bottom of said cup shaped casing member for urging said valve head enlargement against the seat.

2. A valve structure of the class described comprising a cap member having a 25 cylindrical wall portion threaded for engagement on the neck of a receptacle and provided with an outlet aperture in its end, a valve seat surrounding said outlet aperture, a tubular valve stem extended through 30 the valve seat and closed at its outer end, a valve head enlargement on the inner end of 35

the stem engageable against said seat, an expansile coil spring disposed in said tubular valve stem, and acting between the end of said valve stem and the inner portion of 40 said cap member, the coils of the spring being of substantially the same diameter as the inside of said tubular stem, whereby said stem forms a housing and a supporting guide for said spring.

3. A valve structure of the class described comprising a cap member having a cylindrical wall portion threaded for engagement on the neck of a receptacle and provided with an outlet aperture in its end, 45 the material of said cap end being inclined inwardly from said aperture to form a frustoconical valve seat, and then extended outwardly to the plane of the cap end to form an annular shoulder, a tubular valve 50 stem extended through the outlet aperture and having its outer end closed, a valve head enlargement on the inner end of the stem engageable against said valve seat, a cup-shaped casing member having its mouth portion disposed about said shoulder, tabs on the mouth portion of said casing member passed through the end of the cap member, and an expansile spring disposed in the 55 valve stem and casing member for urging said valve head enlargement against the seat.

In testimony that I claim the foregoing I have hereunto set my hand at Milwaukee, in the county of Milwaukee and State of Wisconsin.

JOHN S. BRENNAN.
